UNITED STATES PATENT OFFICE

159,334

GARDEN TOOL OR SIMILAR ARTICLE

Percy J. Gordineer, Niagara Falls, N. Y.

Application June 18, 1948, Serial No. 147,061

Term of patent 7 years

(Cl. D35—2)

To all whom it may concern:

Be it known that I, Percy J. Gordineer, a citizen of the United States of America, residing in Niagara Falls, county of Niagara, State of New York, have invented a new, original, and ornamental Design for a Garden Tool or Similar Article, of which the following is a specification, reference being had to the accompanying drawing, forming a part thereof.

The figure is a perspective view of a garden tool or similar article showing my new design.

I claim:

The ornamental design for a garden tool or similar article, substantially as shown.

PERCY J. GORDINEER.
